WEED DIGGER

Alton R. Hollis, Rte. 1, Hillsborough, N.C. 27278

Filed June 5, 1967, Ser. No. 7,370

Term of patent 14 years

(Cl. D35—2)

I claim:

The ornamental design for a weed digger, substantially as shown and described.
